ENGINE STARTING APPARATUS

John B. Dyer, Pendleton, Ind., assignor, by mesne assignments, to General Motors Corporation, Detroit, Mich., a corporation of Delaware

Application August 4, 1933, Serial No. 683,581

5 Claims. (Cl. 123—179)

This invention relates to engine starter control devices for automotive vehicles and, more particularly, to devices which are adapted to be operated by another controller of the vehicle such as the fuel valve controller or accelerator pedal.

It is among the objects of the present invention to provide a unitary structure adapted to be mounted upon a vehicle and to be connected with means for controlling a part of the vehicle, and including an electric switch for controlling a starting motor whereby the vehicle controlling means may be operated to render the starting motor operative to start the engine. In order that the switch will not be closed by the vehicle controlling means while the engine is running, the structure is provided with means responsive to engine operation for disconnecting from the vehicle controlling means a switch actuator normally connected therewith.

Further objects and advantages of the present invention will be apparent from the following description, reference being had to the accompanying drawing wherein a preferred embodiment of one form of the present invention is clearly shown.

In the drawing:

Fig. 1 is a side elevation of a preferred form of the present invention.

Fig. 2 is a view looking in the direction of the arrow 2 of Fig. 1.

Fig. 3 is a sectional view taken on the line 3—3 of Fig. 1.

Fig. 4 is a sectional view taken on the line 4—4 of Fig. 2.

Fig. 5 is a sectional view taken on the line 5—5 of Fig. 3.

20 designates a frame comprising two U-shaped parts 20a and 20b joined at their yokes by rivets 20c. The part 20a has an arm 21 provided with apertures 22 for receiving screws or the like for attaching the device to some part of the automobile; and is provided with an arm 23 to which a switch case 24 is attached by screws 25 cooperating with nuts 26. The switch case 24 insulatingly supports stationary contacts 27 provided by the heads of terminal screws 28 extending to the exterior of the case 24 and separated by an insulating part 29. The stationary contacts 27 are engageable by a movable contact 30 insulatingly supported by a plunger 31 slidably guided by bushing 32 attached to the arm 23 of the part 20a. A spring 33 normally maintains the contact 30 out of engagement with the contacts 27.

55 Referring to Fig. 2, the frame part 20b has an

arm 40 which supports a stationary shaft or stud 41 upon which are coaxially mounted a bell crank lever 42 and a switch operating lever 43, the latter carrying a lug 44 locatable in the path of movement of the switch operating plunger 31. 5 The lever 43 is provided with a tubular hub 45 which is slidable along the stud shaft 41 in response to movements of a diaphragm 46 swivelly attached to the hub 45 by a rivet 47. The diaphragm 46 forms one wall of a suction chamber 10 10 50 provided between the diaphragm 46 and a stamped metal cup 51 associated with a second metal cup 52 which constitutes a support for the suction chamber 50, the cup 52 being attached to an arm 53 of the frame part 20b by screw 54 15 and nut 55. The diaphragm 46 is urged normally toward the right as viewed in Fig. 3 by a spring 56 located between a washer 57 associated with the diaphragm 46 and a coupling 58 threadedly engaging a bushing 59 attached to the cup 51. 20 The coupling 58 serves to connect the chamber with a pipe (not shown) for connecting the device with the intake manifold of the engine.

Normally the hub 45 is urged into position shown in Fig. 3 by the spring 56. In this position 25 the lever 43 is so located with respect to the lever 42 that lugs 62 of the lever 42 are received within notches 63 of the lever 43. Therefore, when the lever 42 is actuated in a counterclockwise direction as viewed in Fig. 1, the lever 43 will be 30 actuated in this direction and the lug 44 will be caused to engage the plunger 31 of the switch in order to move the contact 30 into engagement with the contacts 27, thereby closing the switch. 35

This device is adapted to be installed in automobiles in such a way that the lever 42 provides a connecting link in a mechanism between the accelerator pedal and the fuel valve of the engine. The switch referred to is used to control the starting motor. Therefore, when the operator moves 40 the accelerator pedal, the engine will be started. When the engine becomes self-operative the suction produced in its intake manifold will be sufficient to cause the diaphragm 46 to be moved toward the left sufficiently to withdraw the lever 43 from engagement by the lugs 62 of lever 42. Thereupon the lever 43 will be free to rotate clockwise to its normal position thereby permitting the starting motor switch to be opened by the spring 50 45 33. The starting motor switch cannot be closed again while the engine is running due to the fact that when the lugs 62 are in alignment with notches 63, the engine throttle will be nearly closed and the intake suction of the engine, when 55

idling, will be sufficient to withhold the lever 43 from the lever 42. In case the engine throttle is open wider and the intake suction decreases sufficiently to permit the spring 56 to move the lever 43 against the lever 42, the ends of the lugs 62 of lever 42 will be engaged by the portions 65 of the lever 43 but the notches 63 thereof will be located out of alignment with lugs 62.

While the form of embodiment of the present invention as herein disclosed, constitutes a preferred form, it is to be understood that other forms might be adopted, all coming within the scope of the claims which follow.

What is claimed is as follows:

- 15 1. Apparatus for controlling the engine starting motor for an automotive vehicle comprising, in combination, a switch for controlling the motor and having an actuator, coaxially pivoted levers one for directly operating the switch actuator and the other for connection with another controller of the vehicle, interengageable members for connecting said levers for simultaneous operation thereof, means for moving one of said levers relative to the other to cause said members to engage, and means responsive to engine operation for moving said one lever relative to said other lever to disengage said members for disconnecting said coaxially pivoted levers.
- 20 2. Apparatus for controlling the engine starting motor of an automotive vehicle comprising, in combination, a switch for controlling the motor and having an actuator, coaxially pivoted levers one for directly operating the switch actuator and the other for connection with another controller of the vehicle, means normally connecting the levers so that the latter operates the former, and means responsive to engine operation for axially moving one of the levers in order to disconnect one from the other.
- 25 3. Apparatus for controlling the engine start-

ing motor of an automotive vehicle comprising, in combination, a switch for controlling the motor and having an actuator, coaxially pivoted levers one for directly operating the switch actuator and the other for connection with another controller of the vehicle, interengageable members for connecting said levers for simultaneous operation thereof, means for moving one of said levers relative to the other to cause said members to engage, and means responsive to engine suction for moving said one lever relative to said other lever to disengage said members for disconnecting said coaxially pivoted levers.

4. Apparatus for controlling the engine starting motor for an automotive vehicle comprising, in combination, a switch for controlling the motor and having an actuator, coaxially pivoted levers one for directly operating the switch actuator and the other for connection with another controller of the vehicle, means normally connecting the levers so that the latter operates the former, and means responsive to engine suction for axially moving one of the levers in order to disconnect one from the other.

5. Apparatus for controlling the engine starting motor of an automotive vehicle comprising, in combination, a switch for controlling the motor and having an actuator, a stud shaft, a lever pivoted upon said shaft and directly engageable with the switch actuator, a second lever pivoted upon said shaft and connectible with another controller of the vehicle, a lug provided by one of the levers and normally received by a recess of the other lever, a spring normally maintaining the levers in operative relation, and means responsive to engine suction for separating the levers and including a diaphragm swivelly connected with the first lever.
